UNITED STATES PATENT OFFICE.

FREDERICK W. WAKEFIELD, OF VERMILION, OHIO, ASSIGNOR TO THE F. W. WAKEFIELD
BRASS COMPANY, OF VERMILION, OHIO, A CORPORATION OF OHIO.

CONVERTIBLE DIRECT OR INDIRECT LIGHTING FIXTURE.

1,160,345.

Specification of Letters Patent.

Patented Nov. 16, 1915.

Application filed January 19, 1914. Serial No. 812,896.

To all whom it may concern:

Be it known that I, FREDERICK W. WAKEFIELD, a citizen of the United States, and a resident of Vermilion, county of Erie, and State of Ohio, have invented a new and useful Improvement in Convertible Direct or Indirect Lighting Fixtures, of which the following is a specification, the principle of the invention being herein explained and the best mode in which I have contemplated applying that principle, so as to distinguish it from other inventions.

The present improvements relate to a convertible direct or indirect lighting fixture for attachment to a suitable fixture support depending from a ceiling or wall. The present popularity of the indirect lighting system has made it desirable to provide fixtures which are suitable for either the direct or indirect method and which can, without change, be assembled for use in either system. The present invention supplies a device for this purpose and one which when used in either system is convenient to assemble and neat in appearance.

To the accomplishment of these and related ends said invention then consists of the means hereinafter fully described and particularly pointed out in the claims.

The annexed drawings and the following descriptions set forth in detail certain mechanism embodying the invention, such disclosed means constituting, however, but one of various mechanical forms in which the principle of the invention may be used.

Figure 1 is a side elevation showing my invention as attached to a fixture support as an indirect light, showing in dotted lines the reflector when swung down into a lower position; Fig. 2 is a section on the line 2—2 in Fig. 1; Fig. 3 is a central vertical section through the reflector; Fig. 4 is a view similar to Fig. 1 but showing the reflector when connected to the support for use as a direct reflector; Fig. 5 is a section on line 5—5 in Fig. 4; and Fig. 6 is a view of the supporting means.

In Fig. 1 there is shown a canopy 1 which will be attached to a ceiling by means of a crow-foot or other connection (not shown) attached to the canopy within the same and a fixture support 2 suitably attached to the canopy and extending downward therefrom. At the lower end of the fixture support 2 there is attached a recep-

tacle 3 in which is carried a lamp receiving socket (not shown). The use of these parts is well known as they are used in almost all depending fixtures for the purpose of enclosing the electrical wires and socket, and their use in the present connection may be taken as merely illustrating one desirable form of such element.

The reflector which forms an essential part of the invention includes a suitable rim 4, preferably circular, provided with a plurality of converging braces 5 which are attached at their adjacent ends to a second and smaller rim 6. Between the braces there is adapted to be received a reflector 7 which is preferably of concavo-convex shape. This reflector may be of a suitably enameled metal or of glass or similar material, and its concave surface must have certain reflecting properties, although the reflector itself will generally be opaque. The reflector is maintained within the braces and in close contact with the same by means of a cup 8 resting against the inner sides of the receptacle adjacent to a central aperture 9 formed in the same. Removably attached to the cup 8 is a tube 10 extending through the aperture in the reflector and being attached externally of the same to a cap 11. This cap 11 fits snugly over a plate 12 attached to the rim 6 about the apex of the reflector. The bottom plate 12 attached to the rim 6 is provided with bayonet slots 13 for the purposes to be referred to herein-after.

The reflector is maintained within the braces by reason of the bent over ends 14 of the latter, within which the reflector is held. On the outside of the rim 4, preferably opposite each of such braces, there is mounted a loop or lug 15 to which is pivotally attached a closed loop 16. Any desired number of these loops may be provided although three will ordinarily be sufficient. When it is desired to use the reflector in the indirect way it is disposed with its concave side facing upward and is maintained a suitable distance beneath the receptacle, in which is held a lamp 17, by means of open ended links or hooks 18 which are removably attached to the loops 16 and also to other loops 19, the latter being pivotally attached to a collar 20 adjustably secured about the fixture support 2. The proper position for the reflector can be set by the ad-

justment of the collar 20 and a convenient method for operating the lamp is by means of a suitable cord passing from the receptacle 3 through the bottom of the reflector 5 through the tube 10 where it may be connected to a button switch, as will be readily understood.

The receptacle 3 receives the lamp socket as stated, which is provided with two 10 pending screws or lugs as shown in Fig. 6 which are adapted to be removably engaged in the bayonet slots 13 formed in the bottom plate 12 of the receptacle or in similar slots formed in a curved collar 21 which is preferably attached to the receptacle to give 15 the same a finished appearance when the reflector is used in the indirect way.

When it is desired to use the reflector in a direct way the cap 11 is removed from the 20 plate 12 by the disengagement of the tube 10 from the cup 8, the two latter members being 25 also removed. The reflector is then positioned with its concave side facing downward and the plate 12 is removably engaged with the usual screws which are to be found in the socket in the receptacle, the collar 21 having first been removed therefrom. The open loops 16 are now 30 swung over to the other or convex side of the reflector and are attached to the loops 19 by the links 18 as before, although it may be necessary to slightly adjust the collar 20 to secure the proper appearance of the links and to permit the same to serve as 35 braces for the outer rim of the reflector.

When used in the indirect way it is often necessary to clean the concave side of the reflector and this may be conveniently done without removing the same by merely unhooking one of the links 18 from the loop 40 16 thus permitting the reflector to tilt down in the position shown by dotted lines in Fig. 1, when the reflector may be conveniently cleaned or a replacement made of a 45 lamp into the receptacle. The present device is extremely neat in appearance whether used as a direct or indirect reflector, and may be conveniently assembled as a part of either system without the use of additional 50 tools or equipment.

Other modes of applying the principle of my invention may be employed instead of the one explained, change being made as regards the mechanism herein disclosed, provided the means stated by any of the following 55 claims or the equivalent of such stated means be employed.

I therefore particularly point out and distinctly claim as my invention:—

60 1. The combination of a depending fixture support terminating in a receptacle and being adapted to receive a lamp, a concavo-convex reflector having an aperture in its center or apex, a plate surrounding such 65 aperture, means attached to said plate and

such receptacle and adapted to engage, thereby supporting said reflector with its convex side uppermost, and connecting means, removably attached to said support and said reflector and adapted to brace said 70 reflector when held with its convex side uppermost.

2. The combination of a depending fixture support terminating in a receptacle and being adapted to receive a lamp, a concavo-convex reflector having an aperture at its center or apex, a plate having bayonet slots surrounding such aperture, such receptacle on said support being provided with lugs adapted to detachably engage in such bayonet slots in said plate, in said reflector, thereby supporting the latter with its convex side uppermost, and connecting means removably attached to said support and said reflector and adapted to brace said reflector when held with its convex side uppermost. 75

3. The combination of a depending fixture support terminating in a receptacle and being adapted to receive a lamp, a concavo-convex reflector having an aperture at its center or apex, a plate having bayonet slots surrounding such aperture, such receptacle on said support being provided with lugs adapted to detachably engage in such bayonet slots in said plate, in said reflector, thereby supporting the latter with its convex side uppermost, and connecting means removably attached to said support and said reflector and adapted to brace said reflector 90 when held with its convex side uppermost. 95

4. The combination of a depending fixture support terminating in a receptacle and being adapted to receive a lamp, a concavo-convex reflector having an aperture in its center or apex, a plate surrounding such aperture, a cap removably attached to said reflector and covering said plate, connecting means removably attached to said support and to said reflector and adapted to support the same below said support with its concave side uppermost, such receptacle 100 and said plate being provided with detachable engaging means whereby said reflector is supported with its convex side uppermost, said connecting means being adapted to detachably engage said reflector when in such 105 last named position.

5. The combination of a depending fixture support terminating in a receptacle and being adapted to receive a lamp; a concavo-convex reflector having an aperture in its center or apex, and a plate having bayonet slots surrounding such aperture; a cap removably attached to said reflector and covering such plate; connecting means removably attached to said support and to said 110 115 120 125 130

reflector and adapted to support the same below said support with its concave side uppermost; such receptacle on said support being provided with lugs adapted to detachably engage in such bayonet slots in such plate in said reflector, thereby supporting the latter with its convex side uppermost; said connecting means being adapted to detachably engage said reflector when in such last mentioned position.

6. The combination of a depending fixture support terminating in a receptacle and being adapted to receive a lamp, a concavo-convex reflector being provided with loops at its rim and having an aperture at its center or apex, a plate surrounding such aperture, connecting means adapted to detachably engage said loops, means attached to said plate and such receptacle and adapted to detachably engage, said means in engaging position being adapted to support said reflector with its convex side uppermost, said connecting means being adapted to support said reflector below said support with its concave side uppermost.

7. The combination of a depending fix-

ture support terminating in a receptacle and being adapted to receive a lamp, a concavo-convex reflector provided at its rim with pivoted loops, and having an aperture at its center or apex, a plate having bayonet slots surrounding such aperture, a cap removably attached to said reflector and covering said plate, other loops attached to said support, open links adapted to detachably engage said last named loops and said pivoted loops, said reflector being supported by said links engaging said loops, with its concave side uppermost, such receptacle being provided with lugs adapted to detachably engage such slots in said plate, said reflector being supported by such engagement with its convex side uppermost, said links being adapted to engage said loops in such last named position of said reflector and being adapted to brace the same.

Signed by me this 15th day of January, 1914.

FREDERICK W. WAKEFIELD.
